BIT

Filed Dec. 29, 1926

Inventor.
Bert Travis.
by Hazard and Miller

Attorneys.

UNITED STATES PATENT OFFICE.

BERT TRAVIS, OF WHITTIER, CALIFORNIA.

BIT.

Application filed December 29, 1926. Serial No. 157,679.

My invention is a bit for well drilling, such as for oil wells, and is particularly adapted for operation in soft formations.

My bit is constructed with a pair of short 5 blades at the bottom spaced apart, these blades merging into a shank, which has deep longitudinal grooves or recesses with a central web and merging into the cap part of the bit. The bit is provided with the 10 usual screw threaded plug to be connected to a suitable socket and with water ducts passing down on opposite sides of the drill. The blades have a horizontal cutting edge which is spiraled inwardly from the outer diameter 15 and each of the blades has a vertical cutting edge which is continued upwardly in the opposite parts of the shank.

My invention will be more readily understood from the following description and 20 drawings, in which:

Figure 1 is a side view, in perspective, of my bit.

Figure 2 is a vertical section taken on the line 2—2 of Fig. 1, in the direction of the 25 arrows.

Figure 3 is a bottom view as if taken in the direction of the arrow 3 of Fig. 1.

The bit is provided with a pair of blade sections 1. These sections merge into the 30 shank 2, the shank having deep grooves or recesses 3, leaving a central web section 4 between the longitudinal grooves. The shank and the web merge into a cap portion 5. A shoulder 6 is formed on top of 35 the cap and a screw threaded plug 7 extends upwardly from the shoulder, being adapted to thread in a socket of the drilling tools. A pair of water ducts 8 extend through the plug, the shoulder and the cap, discharging 40 on opposite sides of the web.

The blades, in detail, are formed with a horizontal lower edge 9 which functions as a bottom cutting edge. This edge is spiraled inwardly from the vertical cutting edge 10 of the blades to the rear portion 11. The vertical cutting edge 10 of the blades is continued upwardly in a vertical line 12, this being the cutting portion of the shank part of the tool. The bit is of the greatest 45 diameter, as indicated in Fig. 3, between the cutting edges. The web portion has a squared lower end 13 and the blades proper on the inside have a sharp shoulder 14 where they join the lower end of the web. The 50 rear face 15 of the blades extends slightly rearwardly of the rear face 16 of the shank

portion of the tool. It will be seen by reference to the circular hole 17 that the side faces 18 of the shank portions are spiraled inwardly to a considerable extent. The lower rear portion of the blade indicated at the part 19 has a considerable concave curve in a vertical direction, as well as the circumferential concave curve, thus forming a species of pocket which draws the material cut inwardly towards the center of the bit.

The web tapers, being narrowest at its lower portion indicated by the numeral 20, and widest at the upper portion 21 where it merges with the cap.

The manner of operation of my bit is substantially as follows:

The vertical cutting edge 10 determines the diameter of the hole being drilled, and the lower edge 9 being spiraled inwardly 75 draws the material cut in an inward direction towards the axial center of the bit. The cutting blades are comparatively short and sturdy as compared with the main body 80 of the shank and web of the bit, this shank being of considerable thickness at the bottom, and thus giving sufficient strength to the blades. The fluid is flushed through the ducts 8, carrying the formation cut upwardly 85 on opposite sides of the bit, there being plenty of clearance on opposite sides of the cap to allow the material to be washed upwardly.

Various changes may be made in the principles of my invention without departing 90 from the spirit thereof, as set forth in the description, drawings and claims.

I claim:

1. A bit having a heavy shank portion joined by a web, there being deep grooves on 95 opposite sides of the web, a pair of blades formed integral with and extending below the shank portion, said blades having an inwardly spiraled lower cutting edge.

2. A bit having a heavy shank portion with a web, there being deep grooves on opposite sides of the web, a pair of blades integral with the shank and extending downwardly therefrom, the blades and the shank having vertical cutting edges, the shank having a portion spiraled inwardly from the vertical cutting edge, and the blades having a lower cutting edge spiraled inwardly to a greater extent than that of the shank.

3. A bit having a pair of lateral shank portions joined by a web, a pair of blades extending downwardly from the shank por-

tions below the bottom of the web, there being deep grooves on opposite sides of the web forming a concave curve transversely on the shank and web portions, each blade and shank portion having a vertical cutting edge in alignment, the blade portions extending to the rear face of the shank portions at the lower end of the web, and the side faces of the shanks being inwardly spiraled, the lower edge of the blades having a cutting edge spiraled inwardly to a greater extent than that of the said side faces.

4. A bit having a pair of shank portions joined by a web, there being deep grooves on opposite sides of the web merging with the shank portions, the lower end of the

web being squared, a pair of blades extending downwardly from the shank portions, each of the blades and its contiguous shank portion having a vertical cutting edge in alignment, the front surface of the groove having a concave curve inwardly from the cutting edge, the lower edge of each blade having a cutting edge forming a sharper concave curve than the curve above mentioned, the front surface of the blades towards their rear end being concaved vertically and horizontally.

In testimony whereof I have signed my name to this specification.

BERT TRAVIS.
